UNITED STATES PATENT OFFICE.

WILLIAM BUCK, OF KILBURN, COUNTY OF MIDDLESEX, ENGLAND.

AUTOMATIC CIRCUIT-CLOSER FOR RAILWAY-SIGNALS.

SPECIFICATION forming part of Letters Patent No. 350,411, dated October 5, 1886.

Application filed December 21, 1885. Serial No. 186,360. (No model.) Patented in England July 6, 1885, No. 8,171.

To all whom it may concern:

Be it known that I, WILLIAM BUCK, a citizen of England, residing at Kilburn, in the county of Middlesex, England, have invented 5 a new and useful Electrical Contact Apparatus Worked by Railway-Trains, (for which I have made application for a patent in Great Britain, dated July 6, 1885, No. 8,171,) of which the following is a specification.

10 In working the traffic on railways, particularly when it is conducted on the block system, it is often desirable that the action of the signals and telegraphic instruments employed should be controlled by the position of trains 15 on the line. In some cases this has been effected by arranging in certain places by the side of the line triggers or treadles, which, when they are acted on by the wheels of a passing train, communicate mechanical movements 20 or transmit electrical impulses for the purpose of locking, unlocking, or moving signals or instruments. It has also been proposed to employ as contact apparatus a box containing mercury with a contact-wire, and a partition so 25 placed in it that on the sudden tilting of the box from a level to an inclined position the mercury makes temporary contact with the wire. This is objectionable, in that the box is liable to accidentally tilt or get out of level, 30 and thereby cease to be effective.

The object of my invention is to improve such contact apparatus, and to render the same safe and certain in operation at all times.

To such ends my invention consists, essential- 35 ly, in coupling the box to the rail in such manner that the depression caused by a passing train imparts a longitudinal reciprocating movement to said box and produces waves in the mercury to make or break contact with a 40 central wire, all as more fully hereinafter described and claimed.

In the drawings, illustrating my invention, Figure 1 is a transverse sectional view of a rail, showing the contact apparatus in elevation; Fig. 2, a side elevation on a reduced scale; Fig. 3, a view similar to Fig. 1, showing a modification of the invention; Fig. 4, a longitudinal sectional view of the mercury-box; Fig. 5, a transverse sectional view of the same, 45 and Figs. 6, 7, 8, and 9 sectional views show- ing modifications in the construction of the mercury-box.

In the drawings it will be seen that between two of the sleepers S that support the rail Ra clamp, A, which is rigidly fixed to the rail, is 55 connected by links B to the short arm of a lever, C, the long upright arm of which carries a box, D, containing mercury. This mercury is arranged, as will presently be described, in such relation to wires E F that the electrical 60 connection of these wires is made or broken by the wave caused by the passage of a train along the rail, the depression of the rail multiplied by the leverage of C, giving to the box D a longitudinal shake, whereby the wave is generated. In a similar manner, if, as shown in 65 Fig. 3, the mercury-box D be carried on a bent spring, G, the longitudinal shake imparted to the box D by the passage of a train will produce a wave of the mercury in the box. 70

It is important that the box and contact-wires should be so arranged as to provide against error arising from alteration in the level or horizontality of the box itself. In order to provide effectually against such errors, 75 the contact is made or broken at the middle of the box, as shown in Figs. 4 to 9, inclusive, so that, the capacity of the box for mercury being symmetrical on each side of the contact-wire, the accidental inclination of the box does not 80 alter the relation of the wire to the level surface of the mercury. Thus in Fig. 4, which is a longitudinal section, and Fig. 5, which is a transverse section, of the box D containing mercury, M, the one wire, E, near the bottom, 85 remains always immersed in the mercury. The other wire, F, is situated in the middle of the box a little above the level of the mercury when it is in repose, so that there is no electrical connection of the two wires. When, 90 however, the box receives a longitudinal shake, the wave produced in the mercury makes contact with F, and so for the time electrically connects E and F. It is found that, as shown in Fig. 6, by inserting in the box a partition, 95 L, dividing it unequally, there is greater certainty of the wave reaching the wire F when a moderate shake is given to the box; or, as shown in Fig. 7, a wedge-shaped obstruction, N, may be placed in the middle of the box, 100

causing the wave to mount over it. When the electrical connection of the two wires has to be broken by the wave, the wire F, as shown in Figs. 8 and 9, is immersed a little in the mercury, either along a partition, P, as in Fig. 8, or without a partition, as in Fig. 9. In that case contact is broken by the uncovering of F when the hollow of the wave comes under it. In all these arrangements of the mercury-box 5 to the wire F is placed in the middle, and consequently the surface of the mercury in repose is always in the same position relatively to the wire, even when the box is not level, but somewhat inclined either way; also, when a partition is used, as in Figs. 6, 7, and 8, there is a hole through the lower part of the partition, which allows the mercury always to take its repose-level, but which does not give so much passage as to affect the operation of the wave 10 in making or breaking contact.

Obviously, when the wire E is intended to connect to earth, instead of employing it as a conductor, the box D may itself be of conducting material. In order more effectually to 15 shake the box D, so as to produce a wave of the mercury, the rail near where it is attached may present a slight hollow or protuberance to be acted on by the passing wheels.

Having thus described the nature of my invention and the best means I know for carrying it into practical effect, I claim— 20

1. An electrical-contact apparatus consisting of a longitudinally-reciprocating box containing mercury and contact-wires, the upper one of which is central and coupled to a railway-rail, said box being reciprocated through the coupling by the depression of the rail to produce waves of the mercury for making and breaking contact with one of the wires, substantially as described. 35

2. The combination, with a railway-rail, of a box containing mercury and contact-wires, the upper one of which is central, a support coupling the box to the rail and operated by the depression of the latter to longitudinally 40 reciprocate the box and produce waves of the mercury for making and breaking contact with one of the wires, substantially as described. 45

In testimony whereof I have signed my name to this specification, in the presence of two subscribing witnesses, this 9th day of December, 50 A. D. 1885.

WILLIAM BUCK.
